To all whom it may concern:

Be it known that I, Pauline Fracchia, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the specific dress disclosed of the specific ornamentation below the front neck portion.
